ABSTRACT OF THE DISCLOSURE

A novel gas-filled overvoltage arrester is disclosed, the overvoltage arrester being characterized by the features that plate-shaped electrodes regarding the fusion process are arranged in a glass body or bulb formed of hard glass, the plate-shaped electrodes possessing rounded edges and at least one millimeter thickness and having a surface area of thirty square millimeters. The plate-shaped electrodes are spaced from one another at a sufficiently small distance to render possible sudden short-circuits due to the formation of a fusion bead at the surface of the electrodes, the thermocapacity of the electrodes being so large that with a current load of ten or more amperes R.M.S. and with more than 1,000 watts per second, the fusion bead positively forms prior to the destruction of the glass body.

The present invention relates to an improved gas-filled overvoltage arrester for protecting low-voltage telecommunication installations and is of the type incorporating two electrodes arranged in a glass bulb. The invention also pertains to an improved construction of electrode assembly for the aforementioned gas-filled overvoltage arrester.

Gas-filled overvoltage arresters have been known to the art for more than twenty years. However, they exhibit an insufficient overvoltage protection because they respond too slowly to steep voltage surges. Attempts have been made to reduce ignition lags by the use of radioactive additives or emitters. In so doing, it was still not possible to eliminate the insufficient current load-carrying capacity. In actual practice, this disadvantage manifests itself in that upon exceeding a predetermined load-carrying capacity limit there appear cracks or complete destruction of the glass bulb occurs without there simultaneously occurring a short-circuit at the electrodes. Due to the entry of atmospheric air into the glass bulb, the operating voltage of the overvoltage arrester considerably exceeded the normal rated value. As a result, further overvoltages are no longer removed so that these steep voltage surges resulted in the destruction of the object to be protected. Even frequent control of the voltage arrester was not able to afford satisfactory security since an arrester which was destroyed by an overvoltage could not be readily perceived by merely visually inspecting such.

Overvoltage or voltage arresters have already become known to the art which exhibit a greater load-carrying capacity. Nonetheless, their security remains limited because even with overloading their operating voltage changes due to deformation of the electrodes or rupture of the glass housing, and without positively leading to a short-circuit. As a result, the object to be protected is no longer protected from further overvoltages.

Accordingly, it is a primary object of the present invention to provide an improved gas-filled overvoltage

2

arrester for telecommunication installations which overcomes the aforementioned disadvantages of the prior art devices.

A further, more specific object of this invention is an improved construction of arrester which positively protects an object from overvoltages and which possesses very high operational reliability.

Yet another very noteworthy object of this invention relates to the provision of an improved voltage arrester which is relatively economical to manufacture, has quite small dimensions yet still possesses a high load-carrying capacity, is extremely reliable in operation and thus requires a minimum of maintenance, and also has a long operating life.

Still a further important object of this invention concerns itself with an improved electrode construction particularly suitable for use with an overvoltage arrester.

The inventive overvoltage or voltage arrester combines the features of high load-carrying capacity and quick response time with the characteristic of instantaneously bringing about permanent short-circuit of the electrodes upon overload without any considerable change of the operating voltage and before another type of destruction of the arrester can occur. The installation to be protected is short-circuited and is, therefore, protected from further overvoltages. Due to the short-circuit which positively occurs in every instance of overload, the defective overvoltage arrester is immediately localized and can be exchanged by the operating personnel.

Generally speaking, the inventive gas-filled overvoltage arrester is characterized by the features that, plate-shaped electrodes regarding the fusion process are arranged in a glass body or bulb formed of hard glass, said plate-shaped electrodes possessing rounded edges and at least one millimeter thickness and having a surface area of thirty square millimeters. Moreover, according to the invention, such plate-shaped electrodes are spaced from one another at a sufficiently small distance to render possible sudden short-circuit due to the formation of a fusion bead at the surface of the electrodes, and wherein the thermal capacity of the electrodes is so large that with a current load of ten or more amperes R.M.S. and with more than 1,000 watts per second the fusion bead positively forms prior to the destruction of the glass body.

Other features, objects and advantages of the invention will become apparent by reference to the following detailed description and drawings in which:

FIGURE 1 is a cross-sectional view of a preferred embodiment of inventive arrester;

FIGURE 2 is a front view of the inventive arrester showing the confronting arrangement of the two spaced electrodes;

FIGURE 3 is a side view of the arrester of FIGURE 2 depicting the manner of connecting the lead-in pin with the associated electrode;

FIGURE 4 depicts the inventive arrester of FIGURES 1 to 3 as arranged in its socket;

FIGURE 5 is a side view of the arrangement of FIGURE 4; and

FIGURE 6 is a top view of FIGURE 4.

Describing now the drawings and initially referring to FIGURES 1 to 3, it will be seen that the inventive arrester comprises a body or bulb 1 formed of hard glass and internally of which the tungsten lead-in wires 3 of the lead-in pins 3b and which are pre-sealed with a glass tube or hose 4 are fused to the glass body 1 by means of these glass tubes 4. The lead-in pins 3b incorporating the tungsten lead-in wires 3 and the therewith connected externally projecting nickel free end portions 7 carry the confronting and spaced substantially plate-shaped electrodes 2 and 2a. The glass tubes or hoses 4 which in-

crease the insulating path between the electrodes 2 and 2a can be seen in FIGURE 2 to project internally of the glass bulb 1 and are fused to its base portion 1a. Both of the electrodes 2 and 2a are advantageously formed of nickel and possess a surface area of preferably 10 x 6 millimeters and a thickness of 2.5 millimeters. They are connected with the tungsten lead-in wires 3 or, for instance, one millimeter diameter, by mechanical wedging, as generally indicated by reference character 5, and are hard soldered or brazed throughout the entire electrode length. Of course, other dimensions for the electrodes are possible insofar as they result in an appropriately high thermal stability and heat capacity. It has been found that these plate-shaped electrodes 2 and 2a should preferably possess a thickness of at least one millimeter with a surface area of at least thirty square millimeters.

The cross-sectional showing of FIGURE 1 depicts the manner in which the tungsten lead-in wires 3 of the lead-in pins 3b are embedded in a respective channel 3a formed at the rear face of the associated electrodes 2 and 2a, whereby there is ensured for good electrical and thermal contact between these electrodes 2, 2a and the lead-in wires 3, and such electrodes during higher thermal loads with discharge arcs are additionally reinforced. It is also possible to apply, in known manner, to the confronting faces of the plate-shaped electrodes 2 and 2a a suitable layer of material 6 favoring emission. As already developed, the outermost portion of free end 7 of the lead-in pins 3b advantageously consists of a nickel wire which can be satisfactorily connected by butt welding 8 with the associated tungsten lead-in wire 3. The fusion bead which short-circuits the arrester upon the appearance of an overload forms in the gap between the activated confronting faces of the electrodes 2 and 2a and, specifically, because of the advantageous inventive feature of rounding the edges 9 of these electrodes 2 and 2a at all sides, as shown, such bead generally appears in the middle of the electrode surfaces.

According to a preferred embodiment of the invention there is employed for the layer of material 6 favoring emission calcium carbonate. This is transformed in the usual manner into calcium oxide. It ensures for a rapid transition of the gas discharge from the glow-discharge phase into the arc phase already at approximately 200 milliamperes as well as a burning voltage which lies such that, by the direct-current voltages which are normally used in telecommunication networks, there occurs a faultless extinguishing of the arrester insofar as such has ignited, that is, the burning voltage lies above the normal supply voltage.

In FIGURES 4, 5 and 6 there is shown an insulating clip or member 12 formed of polyethylene and mounted at the pump tip bulb end 11 of the glass bulb 1. Hooked into this clip 12, or otherwise attached, are both of the nickel contact rails 10 extending along opposite lengthwise sides of the glass bulb 1. This insulation clip 12 thereby serves to fix or interconnect these two contact rails 10 with one another and to also protect the glass bulb 1. At the opposite bulb end, that is, the side remote from the pump tip 11, these contact rails 10 are provided with nickel contact bars 14. These nickel contact bars 14 are connected with the externally extending portion 7 of each of the associated lead-in pins 3b by spot-welding.

The inventive arrester is advantageously filled with a gas mixture consisting of argon, hydrogen and tritium, and with a filling pressure of 80 millimeters mercury pressure. The nickel contact rails 10 together with the clip 12 provide a socket for the arrester and at the same time protect the glass body or bulb 1 against mechanical stress or loads. The arrester thus provided with its socket can be effortlessly and easily introduced into the contact spring fixture of the fuse box. Additionally, this construction renders it easier to undertake any eventually required exchange or replacement of the arrester in the fuse boxes

which normally contain a larger number of such arresters.

While there is shown and described a present preferred embodiment of the invention, it is to be distinctly understood that the invention is not limited thereto but may be otherwise variously embodied and practiced within the scope of the following claims.

What is claimed is:

1. A gas-filled overvoltage arrester for telecommunication installations comprising a bulb formed of hard glass, a pair of substantially plate-shaped electrodes arranged within said glass bulb, said plate-shaped electrodes having rounded edges and each possessing at least a thickness of one millimeter and a surface area of thirty square millimeters, said plate-shaped electrodes being spaced from one another at a relatively small distance sufficient to bring about a sudden short-circuit due to the formation of a fusion bead at the surface of said plate-shaped electrodes, said plate-shaped electrodes possessing a heat capacity which is sufficiently large so that with a current load of at least ten amperes R.M.S. and with more than 1,000 watts per second, the fusion bead positively forms prior to the destruction of said glass bulb, said glass bulb possessing two oppositely situated lengthwise extending sides, a contact rail arranged at each said lengthwise extending side of said glass bulb, said glass bulb further possessing at one end a pump tip, lead-in pins connected to each electrode extending out of said glass bulb at the side opposite to said pump tip, a clip for protecting said pump tip and for affixing said contact rails to said glass bulb at the side of said pump tip, said contact rails being welded at said opposite side to at least one of said lead-in pins.

2. A gas-filled overvoltage arrester for telecommunication installations as defined in claim 1, wherein said lead-in pins are formed of high-melting metal and are connected with each plate-shaped electrode by mechanical wedging and brazing to thereby increase the strength of said plate-shaped electrodes with regard to deformation and at the same time to provide satisfactory electrical and thermal contact between said plate-shaped electrodes and their associated lead-in pins.

3. A gas-filled overvoltage arrester for telecommunication installations as defined in claim 2, wherein said glass bulb is filled with a gas filling primarily containing an inert gas with which there is commingled a gaseous beta-emitter.

4. A gas-filled overvoltage arrester for telecommunication installations as defined in claim 3, wherein said gas filling with which said glass bulb is filled contains a mixture of argon, hydrogen and tritium and possesses a filling pressure of about 80 millimeters mercury pressure.

5. A gas-filled overvoltage arrester for telecommunication installations as defined in claim 2, wherein said plate-shaped electrodes are formed of nickel.

6. A gas-filled overvoltage arrester for telecommunication installations as defined in claim 2, wherein the surface of said plate-shaped electrodes is covered with a layer of material favoring emission in order to accelerate the transition of the gas discharge from the glow discharge phase into the arc phase.

7. A gas-filled overvoltage arrester for telecommunication installations as defined in claim 6, wherein said layer of material favoring emission is formed of calcium oxide.

8. A gas-filled overvoltage arrester for telecommunication installations as defined in claim 2, wherein the rear face of said plate-shaped electrodes is provided with a channel in which there are seated and affixed said lead-in pins.

9. A gas-filled overvoltage arrester for telecommunication installations as defined in claim 2, wherein said plate-shaped electrodes are formed of nickel and said lead-in pins are at least partially formed of tungsten.

10. A gas-filled overvoltage arrester for telecommunication installations as defined in claim 9, wherein said lead-in pins also include a portion formed of nickel defining the free end thereof.
